UNITED STATES PATENT OFFICE.

KATHARINE S. BRYDONE-JACK, OF GLACIER, BRITISH COLUMBIA, CANADA.

DOLL.

Application filed May 3, 1921. Serial No. 466,423.

To all whom it may concern:

Be it known that I, KATHARINE S. BRYDONE-JACK, citizen of the Dominion of Canada, residing at Glacier, in the Province of 5 British Columbia, Canada, have invented certain new and useful Improvements in Dolls, of which the following is a specification.

This invention relates to a child's doll of 10 what may be termed the padded, indestructible class. These dolls are usually made of a material that is receptive of and retains dirt, and on that account they are insanitary and they soon lose in use what 15 little attractive appearance they may have had when first made or purchased, nor is the material such as can be artistically treated.

The doll, which is the subject of this 20 application, is made of a material having a surface which is not receptive to dirt, is therefore lasting in its cleanliness, and when soiled, can be readily washed and its original colour and freshness fully restored. The 25 surface of the material is also such as can be brightly and artistically colored, and the doll is made in a manner that it will retain its original form.

The invention is fully described in the 30 following specification, reference being made to the drawings by which it is accompanied, in which:

Fig. 1 is a front view of a doll made in accordance with my requirements.

Fig. 2 is a cross section of the same.

Fig. 3 is an enlarged detail showing the means by which the hair of the doll is represented.

The body of the doll is constructed of 40 front and back layers 2 and 3 of oilcloth or the like material, wherein a fabric is surfaced with a dressing which is impervious to moisture and impenetrable to dirt. The two layers 2 and 3 are cut and painted or 45 printed to represent the outline of a child or an animal from opposite sides. The hair 6 may be painted or printed on the oilcloth, but is preferably represented with wool or other material of a suitable color, 50 sewn through the cloth and looped on the outer side, somewhat as shown in Fig. 3.

The arms are preferably connected to the body throughout their length, as shown in the drawing, or through the greater part 55 of their length, and the legs, where shown,

may be joined together throughout their length or adjacent the feet, to save them being torn off in the rough handling to which they are exposed.

These front and back portions 2 and 3 are 60 sewn together around their edges as at 4, and the space between the back and front is stuffed with any suitable material in a manner to show the body and limbs in various amounts of bas relief proportioned to 65 the part they represent, that is, without excessive rotundity.

Lines of stitches 5 may be introduced where necessary to indicate the lines of connection of the head and limbs to the body. 70

When completed the entire surface and particularly round the edges, may be varnished not only to protect the paint but to enhance the washable character of the surface. 75

In manufacturing, the material may in sheet form be printed in the colors to represent the parts they are designed to show, and thereafter be cut with dies.

Attention is particularly directed to the 80 sanitary and washable character of the material, and to the artistic finish which that material is susceptible of having imparted to it.

Also to the fact that the parts are edge 85 sewn so as to preserve the contour of the doll under rough usage.

To the manner in which the hair is represented:

To the coloured representation of the flesh 90 and of the material of the child's clothing.

Also to the manner of connecting the limbs to the body or to one another throughout the greater part of their length, whereby untimely destruction is avoided. 95

And finally to the finishing coat of varnish, whereby the edges of the seams are protected both as regards their strength and against the possible adherence of dirt.

A particularly attractive child's toy or doll 100 may thus be made which is free from the numerous objections usually chargeable against dolls of this class.

Although the foregoing description and illustration are particularly directed to the 105 representation of a child, the same construction is also applicable to the representation of animals, with the same advantages.

Having now particularly described my invention, I hereby declare that what I claim 110

as new and desire to be protected in by Letters Patent, is:

A child's doll made of two layers of oil-cloth or the like material each layer cut 5 and painted to represent the outline of the doll from opposite sides, the limbs being connected to the body or to one another

throughout the greater part of their length, said layers being flat seamed together round their edges and lightly stuffed between with ¹⁰ any suitable material and surface coated with a water proofing material.

In testimony whereof I affix my signature.
KATHARINE S. BRYDONE-JACK.
